UNITED STATES PATENT OFFICE.

ROBERT ADAMS, OF SOUTHWARK, COUNTY OF SURREY, ENGLAND.

COMBINED DOOR CHECK AND CLOSER.

SPECIFICATION forming part of Letters Patent No. 437,547, dated September 30, 1890.

Application filed May 18, 1887. Serial No. 238,646. (No model.) Patented in England February 28, 1885, No. 2,718.

To all whom it may concern:

Be it known that I, ROBERT ADAMS, engineer, a subject of the Queen of Great Britain, residing at No. 17 Blackman Street, Southwark, 5 in the county of Surrey, England, have invented certain new and useful Improvements in a Combined Door Check and Closer, (for which I have obtained a patent in Great Britain, No. 2,718, bearing date February 28, 1885,) 10 of which the following is a specification.

This invention relates to certain new and useful improvements in door-checks; and it consists in the novel construction and arrangement of parts hereinafter fully described, and 15 specifically pointed out in the claims, due reference being had to the accompanying drawings, forming a part of this specification, wherein—

Figure 1 is a sectional elevation of the improved self-closing appliance and check. Fig. 2 is a sectional elevation of the cylinder *h* with the internal parts removed. Fig. 3 is a section showing the method of fixing to a door-post. Fig. 4 is a section on the line 1 2 of Fig. 2. Fig. 5 is a section on the line 3 4 of Fig. 2. Fig. 6 is a sectional elevation showing a different method of forming the valved spindle *p* to that shown in Fig. 1. Fig. 7 is a sectional elevation showing the method of 30 forming the cam *k* as a double helix for swing-doors. Fig. 8 is a plan of the block *k* shown in Figs. 7 and 11. Fig. 9 is a plan of the plate *l* shown in Fig. 11. Fig. 10 is an elevation of another method of fitting the door-check 35 to doors, hereinafter described. Fig. 11 is an elevation, partly in section, of the double-acting appliance for swing-doors. Fig. 12 shows the application of the appliance where it is inconvenient to sink an apparatus in or under the floor. Fig. 13 shows its application to an ordinary back-of-door spring. Figs. 14 and 15 show two methods of tightening and regulating the spring shown in Fig. 1.

In Figs. 1, 2, 3, 4, and 5 my arrangement of 45 a combined door spring and check is shown. *h* is a metallic cylinder, closed at its bottom and provided at its top with a cover *i*. *k* is a block having helical groove *k*² and a sleeve *k*', the upper part of said sleeve being fitted with 50 a cap *l* and having a perforated flange *l*'. *p*

is a spindle passing through a suitable perforation in the cover *i* and through the block *k*. Said spindle is bored throughout its length, and is provided with ports *p*' *p*', as shown. A valve-spindle *p*², carrying at its lower end 55 a valve-plug, is fitted within the bore of the spindle *p*, and is turned and regulated by the head *p*³ to adjust the valve-plug toward and away from its seat to regulate the passage of liquid through the ports *p*' *p*'. Instead of forming the valve-spindle with a valve-plug upon its lower end, a ball-valve may be employed and held up to its seat by means of a spring, as shown in Fig. 6. The cap *l* on the sleeve *k*' forms a stuffing-box and is packed 65 at *l*². *m* is an ordinary cup-leather. *n* is a leather washer, and *n*' a metallic washer, both being normally held up in place by means of a spring *n*². The washer *n*' and spring *n*² may, if desired, be dispensed with. The upper part 70 of the spindle is fitted with a leather washer *o* and a metallic washer *o*', which is prevented from turning in the cover by a nib at any part of its circumference. A similar washer *o*² is caused to turn with the spindle by a nib 75 *o*³, engaging with the spindle. *r* is a spiral spring located between the cover *i* and flange *l*', and exerts a downward pressure upon said flange. To the lower end of the spindle *p* is secured a friction-roller *q*², and said friction- 80 roller rests within the helical groove *k*², formed in the block *k*. *q* *q*' are guides formed in one or both sides of the cylinder *h*, with which feathers *q*' *q*' engage and prevent the block from turning. The cylinder *h* is secured to 85 the door-post by means of a flange *h*², and the top of the spindle *p* is secured to the door by means of a similar flange. When the device is designed to be applied to doors which are already provided with springs for closing the 90 same, the spring *r* may be omitted and the cylinder secured to the door-post by means of a flange *h*' and a flange *h*³ screwed to the door, said flange *h*³ having formed integral therewith a collar *h*⁴, which engages with the 95 spindle *p*.

In Figs. 7, 8, 9, and 11 I have shown the combined door-check and spring as being double-acting—that is to say, the block *k* is provided with two grooves, as shown in Fig. 100

7, with which grooves the friction-roller q^2 engages. This form of construction is designed to be employed with doors swinging in both directions, and the roller q^2 engaging with both grooves will cause the door to close when opened from either side. Instead of friction-rollers, pins q^3 may be used, or two rollers or two pins used. In Fig. 11 I have shown both a pin and a roller. In said figure 10 I have also shown the perforated flange l' , made separate from the cup l , and the said flange and cup secured directly to the spindle by means of lock-nuts l^4 l^5 .

In Fig. 12 I have shown a method of fastening the device to the floor. In said figure h^5 is a flange secured to the bottom of the cylinder and designed to be screwed to the floor, and h^2 is a flange on the side of the cylinder screwed to the door-post. h^3 is a plate screwed 15 to the door and engaging the top of the spindle p . Fig. 13 shows the application of the device to an ordinary "back-of-door" spring—that is to say, those springs wherein is employed a spring-actuated arm carrying a roller 20 at its end which presses upon the door to close it.

In Figs. 14 and 15 I have shown two methods of tightening and regulating the compression of the spring, this being accomplished 25 by turning the nut h^2 in the proper direction.

Having thus described my invention, I will now proceed to describe its operation.

The cylinder h is first supplied with a suitable quantity of liquid, and for this purpose 30 oil is preferred, on account of its lubricating qualities and its non-liability to freeze or corrode any of the parts. The cylinder having been fastened to the door-post and the spindle to the door, as above described, upon 35 opening the door the spindle will be rotated, causing the friction-roller to turn in the helical groove, and thus force the block and the perforated flange upward against the spring and compressing the same. During this 40 movement of the parts the fluid above the flange l' escapes through the perforations therein to the bottom of the cylinder, the washer n yielding to uncover the perforations after the manner of a flap-valve. Upon 45 releasing the door after it has been opened the spring r exerts a downward pressure upon the block k through the medium of the flange l' and causes the block to descend, and the descent of the block causes the spindle to rotate, thus closing the door. Upon the descent 50 of the block the washer n will close the perforations in the flange l' , and the fluid beneath the block and said flange will escape through the spindle p and ports $p' p'$ therein to the upper end of the cylinder h ; but owing 55 to the ports being contracted the fluid will escape through them very slowly, offering a resistance to the descent of the block k , and thus allowing the door to close but very slowly 60 and prevent its "slamming."

I claim—

1. The combination of a cylinder or case for containing a fluid, a rotary spindle, a block or piston in the case surrounding the spindle and movable longitudinally thereof by the rotation of the spindle, and a contracted channel for the passage of the fluid from one side of the piston to the other, substantially as described. 70

2. The combination of a cylinder or case for containing a fluid, a rotary spindle, a block or piston within the case surrounding the spindle and movable longitudinally thereof, means for preventing the block or piston turning with the spindle, and a contracted channel for the passage of the fluid from one side of the piston to the other, substantially as described. 75

3. The combination of a cylinder or case, a spindle, a sliding block or piston, a channel connecting the spaces above and below the block or piston, and a valve for closing the channel in the spindle connected with an operating device outside the cylinder or case, substantially as described. 80

4. The combination of a cylinder or case, a rotating spindle therein, a piston sliding on said spindle, and a channel connecting the spaces above and below the piston, the openings to the channel being arranged substantially as set forth. 85

5. The combination of a cylinder or case, a rotary spindle, a block or piston sliding on the spindle and moved by the rotation of the latter, a channel in the spindle opening above and below the block or piston, and an adjustable valve for controlling said channel, substantially as described. 90

6. The combination of a cylinder or case, a spring, a spindle having a fluid-channel therein, a sliding block or piston connected with the spindle, and a valve carried by the piston, substantially as described. 100

7. In a door-check, the combination of a cylinder h , a hollow spindle p , formed with inlet and exit ports p' and provided with friction pins or rolls q^2 , a block k , formed with cam-surfaces k^2 for said pins or rolls to bear against, the flange l' , and passages l^2 , and a washer to bear against the lower side of the passages l^2 to close the same when the two parts are in contact, substantially as described. 110

8. In a door-check, the combination, with a cylinder h and a block k , having cam-surfaces k^2 , of a hollow spindle p , having ports and friction pins or rolls q^2 to bear against said cam-surfaces, and a valve to the passage through the spindle, substantially as described. 120

9. In a door-check, the combination, with a cylinder h , of the hollow spindle p , formed with valve-controlled passages and having friction pins or rolls q^2 , a block k , having cam-surfaces k^2 , and a sleeve k' , a cap l , flange l' , 125

and prevent its "slamming." 130

and passages l^2 , and washers n n' , substantially as described.

10. In a door-check, the combination of cylinder h , hollow spindle p , with pins or rolls q^2 , valve-stem p^2 , with threaded part p^3 , block k , with cam-surfaces k^2 , and a valve for controlling the passages through the hollow spindle, substantially as described.

In testimony whereof I have hereunto set my hand this 14th day of March, 1887.
